GUM-BREAKING MACHINE.

Application filed October 1, 1923. Serial No. 665,836.

This invention relates to a gum breaking machine and more particularly to a machine adapted for use in the manufacture of chewing gum for the purpose of breaking up the sheets of gum into the form of sticks for introduction into a wrapping machine.

In the manufacture of chewing gum the final operation of preparing the gum for wrapping, is that of breaking up the scored sheets into stick form. A sheet may consist of any number of connected sticks, but for the purpose of describing the machine embodying the invention, a sheet will be considered as consisting of a row of 25 sticks connected along their side edges. The sticks are usually fed into the wrapping machine by means of a vertical chute in which the sticks are piled one upon the other.

Heretofore it has been the practice to break up the sheets by hand and feeding them to the wrapping machine, and in the following manner: A pile of sheets of say 10 or 12 in number, are broken up simultaneously by bending and then breaking successive vertical rows of sticks from one end of the pile, these vertical rows being introduced in the feed chute of the wrapping machine.

The object of this invention is to provide a machine which will accomplish the same work heretofore accomplished by hand, but characteristic of labor saving machines; it is automatic in its operation and is capable of handling much larger quantities of gum than is possible by hand labor. The machine is designed to eliminate all handling of the gum other than maintaining a supply of sheets in a magazine provided for the purpose.

A preferred embodiment of the invention will be described in connection with the accompanying drawings in which:

Fig. 1 is a general view in front elevation of the machine;

Fig. 2 is a top plan view of the machine.

Fig. 3 is a view of the machine in rear elevation.

Fig. 4 is a view in horizontal section of the machine as taken on line 4, 4 of Fig. 3.

Fig. 5 is an enlarged detailed view in front elevation of the pile supporting table and breaker mechanism during the sheet feeding operation.

Fig. 5^a is a cross sectional view taken on line 5^a, 5^a of Fig. 5. 55

Fig. 5^b is an enlarged detailed view of the locking device associated with the breaking mechanism, in the positions occupied during the sheet feeding operation.

Fig. 6 is a view similar to Fig. 5 as showing the same parts in the next advanced position and immediately before the breaking operation takes place. 60

Fig. 6^b is a detailed view corresponding to Fig. 5^b and showing the positions of the locking device when the breaking mechanism is in the position shown in Fig. 6.

Fig. 7 is an enlarged detailed view of the breaking mechanism immediately after the same has engaged and bent a vertical row of sticks from the end of the pile and immediately before the same is gripped in the breaking mechanism. 70 75

Fig. 7^a is a detailed view of the breaker locking mechanism in the position occupied when said breaker is in the position shown in Fig. 7.

Fig. 8 is a detailed view corresponding to Fig. 7, with the breaker mechanism in its retracted position and immediately before the gum is ejected into the chute of the wrapping machine. 80

Fig. 8^a is a view in vertical section corresponding to Fig. 5^b and showing a sheet being fed onto the pile after the breaking operation. 85

Fig. 9 is a perspective view of a pile of sheets showing the arrangement thereof, as 90 they are advanced toward the breaking mechanism.

Fig. 10 is a perspective view of a vertical pile of sticks as they are arranged in the breaking mechanism immediately before 95 they are ejected therefrom, and

Figs. 11 and 12 are detailed views of the sticks immediately before and after bending and showing the manner in which they are broken by the action of the breaking mechanism. 100

Before describing the construction of the machine, a clearer understanding will follow from a brief consideration of the principle involved. Referring immediately therefore 105 to what will hereinafter be termed the gum

pile A, Figures 1 and 9, and assuming as a unit, a sheet of gum *a* consisting of twenty five (25) connected sticks *b*, the sheets are fed into a magazine B located just above and to the rear of the pile A. The pile A, is decreased in thickness from left to right, being twenty five sticks high at the left hand or forward end and decreases by one stick until it is reduced to one sheet at its right or rear end. To describe it in another way the pile is so arranged that the top most sheet is twenty five sticks long and the length of each succeeding sheet is reduced by one stick so that the lower most sheet is a single stick located at the extreme left forward end of the pile.

The machine operates in cycles, each cycle consisting of the following major operations; 1—the feeding of the sheet from the magazine on to the top of the pile A; 2—the advancing endwise or forwardly of the entire pile A a distance equal to the width of the single stick; 3—a rocking forward and in the opposite direction to movement of the gum pile, of the breaking mechanism C which grips the vertical row of sticks A' at the forward end of the pile, breaks them off and recedes to its initial position; and 4—the ejection of the detached pile in a lateral direction from the breaking mechanism and by suitable ejector into the vertical chute D leading to the wrapping mechanism.

From the foregoing it will be seen that the method of piling the gum is an important feature of the machine, this arrangement being characterized as a continuous process of alternately adding horizontal rows of twenty five sticks to the top of the pile, and removing vertical rows of the same number of sticks from the end of the pile. Thus it will be seen that each sheet is shortened by one stick during each cycle until it reaches the bottom of the pile in the form of a single stick and is finally consumed completely.

With these introductory explanations and the principal parts of the machine identified, the structural features of the machine may now be described.

While the machine may be constructed as a complete unit, it is illustrated as a part of a wrapping machine and therefore will be described as such.

The wrapping machine is indicated in Figure 1 by a vertical pedestal E, and forms a support for the breaking machine, which rests upon an under frame or bracket 1, secured to, and extending outwardly from the part E of the wrapping machine, said bracket having a base plate 1^a to which the frame of the breaking machine is fastened. The breaking machine consists primarily of vertical uprights or end frame members 2, 2, and a transverse frame member 3, extend-

ing between the upper ends of the vertical member 2, 2, and supporting the magazine B and operating parts associated therewith. These frame members form the essential parts of the machine frame, although there are various arms and brackets bolted or otherwise secured to these frame members for supporting the various operating parts of the machine.

The driving mechanism is of the type usually employed in machines of this character, the primary driving elements being supported upon the base plate 1^a and comprising a main drive shaft 4, operatively connected with a suitable source of power such as a motor or the driving mechanism of the wrapping machine. The main shaft 4 extends longitudinally of the machine and at its outer end carries a bevel gear wheel 5 which meshes with a beveled gear wheel 6 keyed to a counter shaft 7. Mounted on the counter shaft 7, are two cam wheels 9 and 10, which operate the breaker mechanism and breaker lock, respectively, as hereinafter to be described. Just forwardly of the cam wheel 9, is keyed a sprocket wheel 11, carrying a sprocket chain 11^a having driving connection with the gum pile transporting mechanism.

Keyed to the main shaft 4 is a cam wheel 12, having cam grooves on both faces, which operate the gum feeding mechanism associated with the magazine B. Immediately adjacent and to the right (Figure 4) of the cam wheel 12, is another, but single cam wheel 13, operating the presser block mechanism associated with the gum pile.

The cams are of a familiar type, being designed to translate rotative motion into intermittent reciprocatory motion. The cam 10, is typical of the type used. The cam wheel is provided with annularly grooved hub 10^a in which rides a yoke 14 affixed to the lower end of a rock shaft 15, extending to the particular member or mechanism to be operated. In the face of the cam is an irregularly shaped groove, in which rides a cam roller carried by the yoke 14, said groove and roller coacting to impart the desired motion to the rock shaft during a single revolution of the drive shaft. Although each cam performs a different operation, the general arrangement described is typical of all, therefore it is proposed to omit a detailed description of each cam, except to point out any peculiarities that may exist in connection with any particular cam.

Referring now to the gum feeding and piling mechanism, the same comprises first, the gum magazine B, consisting of vertical back and end walls 16 and 17 (Figure 5^a) and a relatively short front wall or dam 18. The bottom wall of the magazine is formed by two superimposed edgewise sliding plates 19 and 20, the upper plate being

termed the pusher plate and the lower, the carrier plate. The magazine and parts associated therewith are mounted upon the cross member 3 of the frame, and just rearwardly of the gum pile supporting plate 21, consisting of three inclined bars 21^a spaced apart in parallel relation.

Coacting with the supporting plate 21, is a pair of transporting members 22, 22^a consisting of bars, arranged on edge in the slots or spaces between the bars 21^a of the plate 21 and provided along their edges with steps corresponding to the under surface contour of the gum pile A. The number of steps corresponds to the number of sticks in a sheet of gum, namely, twenty five (25) as shown in Figure 5. Intermediate the ends of the transporting bars are pairs of depending arms 23 having pivotal connection with the ends of vertical links 24, 24, which in turn have pivoted connection with a horizontal pitman or connecting rod 25, journalled at its ends upon the faces of two crank disc 26, 26 journalled upon the frame members 2, 2, carried by the crank disc 26 (to the right and above the counter shaft 7, Figure 1) is a sprocket (not shown) which meshes with the sprocket chain 11^a leading from the driving sprocket 11 on said counter shaft 7.

Referring again to the magazine B, it has already been pointed out that the bottom thereof consists of two superimposed plates 19 and 20. In a word, these plates are slideable endwise outwardly through a slot 27 (Fig. 5^a) formed between the front wall or dam and the vertical wall 28 extending upwardly from the pile supporting table 21 and in the plane of the top of the pile A. The bottom or carrier plate 20 is secured and carried upon a pair of guide bars 29 which slide within guide slots 3^a formed in the upper face of the transverse frame member 3. The guide bars 29 extend rearwardly and are connected with rocker arms 30 through the medium of short links 31.

The upper or pusher plate 19 is actuated in a somewhat similar manner, being attached along its rear edge to a bar 32, which engages a fixed guide bar 33 extending horizontally and rearwardly from the rear wall 16 of the magazine and bolted in place. The bar 32, has a pair of integral arms 32^a, 32^b, connected with a pair of rocker arms 34, 34, through the medium of links 35. As shown in Fig. 3 the rocker arms 34 are included between the rocker arms 30—30 and joined together by means of a web 36, thereby uniting the arms as a rigid frame. The lower ends of the rocker arms 34—34 are journalled upon a shaft 37 extending lengthwise of the machine and near the base thereof, there being suitable brackets 38—38 bolted to the frame members 2—2 for supporting this shaft. The lower ends of the arms

34—34 have a form of hubs 34^a and integral with one of the hubs, namely that shown at the right in Fig. 3, is an arm 39 extending downwardly with a slight forward inclination, said arm carrying at its end a cam roller (not shown) engaging a cam groove (not shown) formed in the right hand face of the large cam wheel 12.

The rocker arms 30—30 are fastened or non-rotatably mounted at the ends of the shaft 37 and are actuated by the rotation thereof. Secured to the shaft 37 and intermediate its ends is a sleeve 40, having an integral arm 41 depending therefrom and inclined in a forwardly direction. This arm likewise carries at its end a cam roller which rides in the cam groove formed in the left hand side of the large cam wheel 12. Thus the shaft 37 provides a journal for the rocker arms 34—34, as well as the rocker shaft 75 for the rocker arms 30—30 fixed thereto. The movement or oscillation of the pairs of rocker arms 30 and 34 are manifestly dependent upon the shape of the groove in the cam wheel 12.

The manner in which the sheets of gum are discharged from the magazine B, will be understood from the following:

In Fig. 6^a the parts are shown in a position immediately before the pusher and carrier plates begin their forward stroke to discharge a sheet of gum from the magazine. It will be noted that the pusher plate 19 is fully withdrawn and its forward margin adjacent the rear wall 16 of the magazine. The carrier plate 20 extends throughout the bottom of the magazine with its forward edge substantially in line with the discharge slot 27. In this position a sheet of gum a is permitted to drop onto the carrier plate and immediately in front of the pusher plate 19. As soon as the bottom sheet is in position the pusher and carrier plates move forwardly together carrying the bottom sheet of gum outwardly through the slot until they reach the positions shown in Fig. 8^a, the pusher plate being advanced until its forward edge reaches the slot 27 and the carrier plate extending beyond the slot the full width of the gum pile A. The carrier plate then moves rearwardly, depositing the sheet of gum upon the gum pile whereupon the pusher plate is retracted allowing the next sheet in the magazine to drop onto the carrier plate and in front of the pusher plate. In other words the parts are moved from the positions shown in Figure 5^a to the positions of Figure 6^a.

The function of the carrier plate is to carry the sheets forwardly and deposit them upon the gum pile, without subjecting them to the detrimental effects of sliding them in contact with a fixed bottom plate and thus removing the protective coating with which the sheets are covered. This is particularly

desirable, owing to the weight of the sheets which are piled upon the bottom one. Thus, the only friction occurring between the sheets is between the upper surface of the bottom sheet and the under surface of the sheet above. In this connection, it is observed that the corner of the front wall or dam 18 is cut away along an oblique line as at 18^a (Figure 5^a), thus permitting the lower sheets to assume a stepped relation for the purpose of preventing the pile in the magazine from being disturbed and the uniform feeding interrupted.

Manifestly, the movement of the pusher and carrier plates takes place at a definite interval in the cycle of operation as will later be set forth, in considering the action of the entire machine. For the present, therefore, it is sufficient to point out the fact that immediately after each sheet is ejected from the magazine B and deposited on the top of the gum pile A, that said pile is moved bodily in an endwise direction to the left. Thus, referring to Figures 5 and 6, it will be observed that the transporting bars 22 have been brought upwardly into contact with the under side of the pile A, each notch or step therein engaging the rear-most edge of each successive sheet or layer constituting the pile. As already pointed out, the pile A decreases in thickness from left to right and each sheet or layer from bottom to top, projects beyond the right hand end of the sheet immediately below, a distance equal to the width of a single stick of gum. Thus, as the transporting bars 22—22 engage the under side of the pile the whole is moved endwise and to the left from the full line position to the dotted line position of Figure 5, the full amount of the advance being equal to the width of the row of sticks at the forward end of the pile. The transporting bars 22 are actuated through the medium of the sprocket chain 11^a, the crank disks 26, the connecting rod 25, and the links 24, said bars describing a circular path in a counter clockwise direction, although in all positions of movement they are parallel with the bottom of the gum pile. Thus, so far as the advancing of the gum pile and the replenishment thereof from the magazine is concerned, the action is that of alternately depositing a sheet on to the pile and then advancing the pile bodily to the left for the purpose of presenting the end row of sticks for removal by the breaking mechanism "C".

There are certain auxiliary devices which co-operate with the sheet feeding and pile transporting magazine which may be described at this point. Again referring to Fig. 5, there will be observed at the right hand end of the gum pile, a lever arm 42 pivoted at its lower end at a point some distance below the end of the gum table and, as more clearly shown in Fig. 1, is mounted

to the side of the vertical frame member 2. The upper end of the lever 42 is bent inwardly at right angles to form a transverse stop member 42^a. Connected with the lever arm is a light coil spring 43 which acts to exert a force intending to hold said lever arm inwardly and toward the left. Immediately below the spring is an adjustable set screw 44 arranged at right angles to the lever arm 42 and serving to limit the movement of said lever arm to the left and under the action of the spring 43. Mounted at the end of one of the transporting bars 22 is a projecting lug 45 adapted to engage the lever arm 42 during each revolution of said bar, and for the purpose of moving it to the right during the period that a sheet of gum is being delivered to the gum pile. The lever arm is set so that the stop member 42^a is in vertical alignment with the right hand extremity of the topmost sheet of gum, so as each sheet is delivered, the lever arm 42 is carried inwardly and in the event that said sheet is not properly located, it will be moved endwise by the lever arm 42, thus insuring the proper placement of each sheet as it is delivered from the magazine.

Located near the front end of the gum pile is a presser or clamping plate 46, adapted to be rocked or oscillated through a small arc into and out of contact with the top of the gum pile. As shown in Figs. 1 and 5^a, the plate is formed integral with a bell crank lever 47 journalled upon a horizontal rock shaft 48 and supported upon a bracket 49 bolted to the front face of the machine frame. The bell crank lever 47 is pivotally connected at its lower end to a push rod 50, having a yoke 52, mounted at its lower end which co-acts with a cam wheel 51 keyed to the main drive shaft 4. This cam functions in the same manner as already described to oscillate the clamping plate at a predetermined interval in the operation of the machine. The clamping plate proper consists of two parts, namely, a fixed plate 46^a and a yieldable plate 46^b, the latter being relatively thin and separated from the fixed or main plate by means of a number of short coil springs 52—53. The yieldable plate 46^b is further connected to the main plate by means of bolts 54, extending through apertures through the plate 46^a and anchored in the plate 46^b. As shown in Fig. 5^a the clamping plate occupies an inclined position wherein it is raised above the top surface of the gum pile. During this interval a sheet of gum is deposited upon the pile and immediately thereafter the pile is advanced and then the clamping plate is brought down in contact with the pile and to the position shown in Fig. 6^a. The pressure exerted by the clamping plate holds the pile tightly against the supporting table and prevents the same from being lifted or other-

wise disturbed during the breaking operation hereinafter to be described.

To insure the positive action of the clamping plate, a heavy coil spring 54 is connected with the lower end of the bell crank lever 47, the same extending downwardly and fastened to the frame member 2 at a point immediately below and offset inwardly from the lower end of the bell crank lever.

10 A third auxiliary member co-acting with the gum pile advancing mechanism is a pair of levers 55 carried upon the gum table and pivotally connected near their left hand ends to the inner face of the bars 21^a of said gum table as shown in Fig. 5^a. Each lever 55 has a sharpened point extending in a general upwardly direction and adapted for contact with the under side of a single stick of gum constituting the undermost and foremost 15 layer of the gum pile. This lever normally assumes a position immediately below the gum pile and parallel with the gum table, and engages the rearmost stick of the second layer from the bottom (consisting of two 20 sticks), just prior to the breaking operation, whereupon the remaining single stick becomes the bottom layer. During the advance movement of the pile the rear ends of the 25 levers are depressed so as to disengage the pointed ends from the advancing stick. A small coil spring 56 is connected intermediate the free end and fulcrum point of the lever, and is anchored at a suitable point directly there below. This spring serves to 30 yieldingly hold said lever in depressed position. Carried upon each of the transporting bars 22 immediately adjacent the levers, is a laterally extending lug or pin 57, (Figures 35 6 and 7) which come in contact with the underside of the lever just an instant before the pile is moved bodily forward, thus lifting the depressed end of the lever and withdrawing the pointed end from the bottom layer of gum, consisting, as clearly shown in Figure 40 7, of a single remaining stick. The purpose of this auxiliary lever is to hold the single stick in position, which, due to its extreme short length is liable to be displaced relative 45 to the remainder of the pile.

Having considered the gum piling and advancing mechanism, the mechanism for breaking the vertical rows of sticks from the end of the pile A will now be described. This mechanism has heretofore been referred to as the breaker C located at the left hand end of the pile A, Figure 1. The main supporting member for the breaker mechanism is a rock shaft 60, extending crosswise of the end of the machine and rearwardly of the forward or left end of the gum pile supporting table. The rock shaft is journaled in suitable journal bearings, 61, 61 secured to the machine frame.

60 Mounted upon the rock shaft 60, are two rocking frames 62 and 63, the former being

fixed or keyed to the shaft through the medium of hubs 62^a engaging the shaft at its ends and central portions, the intermediate hub having a pin 62^b extending through it and the shaft. The frame 63 is journaled upon the rock shaft, by means of bearing sleeves 63^a, 63^a, on either side of the intermediate hub 62^a of the frame 62.

The rock frames 62, and 63, are generally 75 rectangular in shape and of a skeleton structure consisting of a bar extending parallel to the shaft 60 and arms extending from the ends and center of the bar, and connected with the hubs and bearing sleeves 62^a and 63^a. The frame 62 is disposed radially with respect to the rock shaft 60, whereas the frame 63 is offset slightly below the shaft by short radial arms 63^b connecting the frame 63 with the bearing sleeves 63^a thereof.

80 The function of the frame 62 is two-fold: it carries at its forward end, the breaker member 64, and at its rear or opposite end, a locking device for momentarily locking the frame and the directly connected breaker member 64, in both the forward and reverse position of its rocking movement. The locking device and its purpose will be set forth presently.

85 The breaker member 64, consists of a frame, having a width substantially equal to that of the gum pile A arranged at an oblique angle to the frame 62 to which it is rigidly connected by suitable connecting means.

90 At the lower edge of the breaker frame 64, is a laterally extending jaw 64^a terminating at its forward edge opposite the edge of the gum supporting table 21, and in alignment with the axis of the rock shaft 60, as shown in Figures 5 to 8 inclusive. The jaw 64^a forms an integral part of the breaker frame which also includes a back plate 64^b inclined rearwardly at an angle of about 30° to the vertical when the top surface of the jaw 64^a is horizontal as shown in Figure 5. The jaw 64^a and back plate 64^b form two 100 sides of a rectangular cavity or recess which embraces the end row of sticks of the gum pile at each forward oscillation of the breaker frame, the third or top member being a movable jaw 65, located opposite the lower jaw 64^a and spaced above it a distance substantially equal to the height of the forward pile of sticks of the gum pile A. The movable jaw member consists of vertically 105 sliding blocks 65^a, 65^b, one above the other and separated by coil springs 66. The lower block has an oblique under surface parallel to the top surface of the lower jaw. The blocks are movable through a limited distance by a toggle device, (Figs. 7 and 8) arranged as follows: A pair of toggle links 67, 67, are located just above the movable jaw 65, and centrally of the breaker frame, one of said links being pivotally connected to the upper block 65^a and the other at a fixed point 110

115

120

125

130

67^a at the upper edge of the frame in line with the movable pivot point. The inner ends of the link are pivotally connected together and at the end of a transverse link 68 extending rearwardly through a slot 69 in the breaker frame and pivotally connected to the frame 63.

Thus it is seen that the breaker member 64, is actuated as part of the frame 62, about 10 the axis of the rock shaft 60, and the frame 63, while it also rocks about the same axis, described as slightly different path due to its offset relation to the rock shaft. Moreover, it is seen that the frame 63, is indirectly connected with the breaker frame 64, through the medium of the link 68, the toggle levers 67, and the movable jaw 65 of the breaker member. Thus the relative movement of the frames 62 and 63 actuates 20 the movable jaw to grip and release the piles of gum as they are broken from the end of the pile A, and swung rearwardly to ejecting position.

It is important now to observe the manner 25 in which the breaker mechanism is actuated. Referring to Figures 1 and 5, a push rod 70 extends obliquely across the front of the machine, from a cam wheel 71 mounted on the counter shaft 7, to a link pivotally connected to the lower portion of the frame 63. The push rod is actuated with a reciprocating movement through the medium of a yoke 73, coaxing with the cam wheel 71, in the same manner as the cams heretofore 30 described. The movement of the frame 63, is therefore a rocking or oscillatory movement about the rock shaft 60, the forward and rear position being shown in Figures 6 and 7 respectively. The breaker member 64 35 is rocked or oscillated indirectly through the connecting link 68, from the upper end of the frame 63, to the toggle levers 67, 67, and thence through the breaker frame 64 to the frame 62 itself, its movement being derived entirely from the movement of the positively actuated frame 63, although due to the flexing of the toggle links the two frames do not rock together. This is important 45 since the gripping action of the jaw 64^a and 65 is dependent upon relative movement of the oscillating parts.

The action of the breaker mechanism as thus far described will be understood from the following:

50 During the advanced movement of the gum pile by the action of the transporting bars 22, which momentarily engage the bottom of the pile and then recede, in their circular movement, the breaker member is in the position shown in Figures 5 and 6, and about to be moving upward to the position shown in Figure 7.

Assuming that the gum pile A has been advanced endwise and toward the breaker member 64, to the position shown in Fig. 6,

it will be seen the foremost portion is carried onto the lower jaw 64^a of the breaker frame 64, and further, that the end surface of the pile is inclined to the vertical and in a direction away from the breaker. In this 70

position the breaker member is about to start its movement toward the pile A, the movement being transmitted to the breaker frame, from the rock frame 63, through the link 68 and toggle links 67, 67 which are flexed, 75

so that the movable jaw 65 is drawn upwardly and the recess therein opened to its fullest extent. As clearly shown in Figure 7, initial contact of the breaker member with the gum pile bends the forward row of 80 sticks A' upwardly at an angle of about 45° to the horizontal, this being sufficient to partially break the several sticks along the score lines. This action is more clearly shown in Figures 11 and 12, in which two 85 single sticks are shown before and after the bending operation. The bending action is manifestly accompanied by a shifting of the sticks in the plane of their contacting surfaces, and for this reason the jaw 65 is 90 retracted so that no pressure is applied from the top during the bending operation. However when the bending has been completed and the breaker member has reached its full advanced position Figure 7, there takes place 95 a relative movement between the frames 62 and 63, consisting of a slight retraction of the frame 63, while the breaker member remains stationary. This relative movement is clearly represented by the dotted line position of the arm of the frame 63, in Figure 100 7, and this movement is sufficient to straighten the toggle links and bring the jaw 65 into gripping contact with the vertical row of sticks A', as shown in dotted lines Figure 7. Inasmuch as the movement of the breaker frame 64 is derived through the frame 63, and the connecting link 68, it is necessary to momentarily lock the breaker frame so as to obtain the relative movement required to straighten the toggle links. This is the function of the locking device which will be hereinafter described, but for the present it can be assumed that the instant the gripping takes place the locking 110 device releases and the breaker moves away from the pile A, thus completely severing or pulling the row A' away from the pile and carrying it to the position of Figure 8. During the return movement the toggle 115 levers 67, 67 remain in straightened position, thus holding the jaw 65, in clamping engagement with the row A' which now assumes the arrangement of sticks shown in Figure 10.

At this point, there is another slight forward movement of the frame 63, relative to the breaker member, which is sufficient to flex the toggle links 67, 67 thereby releasing the grip of the movable jaw 65, with the 120 125 130

vertical row or stack A', this flexing being brought about by the locking of the frame 62 and breaker member 64, by the locking device.

6 The row of sticks A' are now free to be ejected from the breaker member 64, which step immediately follows and during a period of momentary rest of the breaker member before beginning another forward oscillation.

10 The ejector mechanism is clearly shown in Figs. 2, 3 and 5 and consists of an ejector bar 73 slidably mounted in suitable guides 74 on the frame 62, parallel with, and adjacent to, the rock shaft 60. The ejector bar extends substantially the length of the frame 62, and carries at its forward end, an ejector plate 75, normally positioned in the plane of the rear edge of the breaker member 64 and at all times in alignment with the gum recess thereof. At the rear end of the ejector bar 73, is a radial forked arm 75, which straddles an ejector actuating bar 76, extending endwise from the adjacent rear corner of the carrier plate 20, associated with the sheet feeding mechanism, and rigidly secured thereto. The actuating bar is curved along its underside in the arc of a circle concentric with the axis of the rock shaft 60, as shown in Figure 3, thus allowing the ejector bar to swing relative to the actuating bar during its oscillating movement with the frame 62.

Bearing in mind that the carrier plate 20 reciprocates intermittently to feed the sheets *a* from the magazine B onto the gum pile A, it is manifest that the ejecting operation takes place at the same time, thus as a sheet *a* is fed onto the gum pile an equivalent volume of gum in the form of a stack A' of separate sticks is, at the same time ejected from the breaker, by the simultaneous forward movement of the ejector bar 73 and plate 74, into the upper end of the chute D, located just forwardly of the breaker mechanism C (Figure 8^a).

The locking device which coacts with the breaker mechanism to momentarily lock the breaker member 64, in its forward and rearward positions will now be described. It has already been explained that the locking of the breaker member 64 is provided for in order to bring about the relative movement between the breaker 64 and the actuating frame 63, at the end of the forward and return strokes, in order to operate the toggle links 67, 67, which in turn actuate the movable clamping jaw 65, to grip and release the stacks of sticks A' after they are broken from the end of the pile A.

60 The locking mechanism is located at the rear end of the rock shaft 60, and comprises a sector 77 formed integral with the hub 62^a at the rearmost end of the rock frame 62. This sector is provided at its edge with

a laterally and rearwardly projecting locking flange 77^a concentric with the axis of the rock shaft 60. The sector manifestly oscillates with the frame 62 and likewise with the breaker member 64, so that any locking action upon the sector acts to lock all of these parts from movement about the shaft 60. Beyond the hub 62^a with which the cam sector 77 is integral, is fixed collar 78, pinned to the shaft 60, and having an annular groove, in which rides the forked end or yoke 79, of a reciprocating locking plate 80 mounted at the end of the rod 15 (Figures 2 and 3) and which has already been described in connection with the cam 10. Formed integral with the plate 80 and projecting from the inner face thereof into the path of the locking flange 77^a of the sector 77, are two locking lugs 80 and 82 (Fig. 5^b) spaced apart longitudinally and located adjacent the opposite sides edges thereof. These lugs are adapted to engage the ends of the locking flange 77^a and to thereby lock the frame 62 from movement, as will be understood from the following:

90 Referring to Figure 5^b the locking members are shown in position corresponding to the positions of the breaker mechanism parts in Fig. 5 in which the breaker has just released a stack of sticks A' and ejected them into a substantially horizontal position and the rod 15 has come to rest at the end of its upward stroke, thereby bringing the lower lug 81 into abutting engagement with the end of the locking flange 77^a. So long as the lug remains in this position the frame 62 is held from movement, but only for an instant, for the rod 15 immediately begins its downward stroke thereby withdrawing the lug 81 from the path of the flange. Immediately thereafter the frame 62 is oscillated forwardly toward the gum pile, carrying the flange 77^a downwardly in a clockwise direction between the lugs 81 and 82, as shown in Fig. 6^b, and the breaker member 64 forwardly (Figure 6) until it reaches the position of Figure 7,—the limit of its forward movement. In the meantime the parts of the locking device have been shifted to the position shown in Fig. 7^a, to wit: The flange 77^a has cleared the path of the upper lug 82, which immediately thereafter, is moved from the full to the dotted line position of Figure 7^a by the quick return movement of the rod 15. At this point the rearward movement of the frame 63 begins, but the breaker frame 64 is locked against movement by the lug 82, thus permitting the frame 63 to take the dotted line position of Figure 7, which is sufficient to lock the toggle levers 67, 67 (as shown in Figure 8) and thus clamp the stack A' between the breaker jaws. An instant thereafter the rod 15 shifts upward.

95 100 105 110 115 120 125

10 The locking device which coacts with the breaker mechanism to momentarily lock the breaker member 64, in its forward and rearward positions will now be described. It has already been explained that the locking of the breaker member 64 is provided for in order to bring about the relative movement between the breaker 64 and the actuating frame 63, at the end of the forward and return strokes, in order to operate the toggle links 67, 67, which in turn actuate the movable clamping jaw 65, to grip and release the stacks of sticks A' after they are broken from the end of the pile A.

60 The locking mechanism is located at the rear end of the rock shaft 60, and comprises a sector 77 formed integral with the hub 62^a at the rearmost end of the rock frame 62. This sector is provided at its edge with

ly again, withdrawing the lug 82 from the path of the locking flange 77^a and the frame 62 is permitted to be carried rearwardly, said flange 77^a passing between the lugs 81 and 82 as before, again returning to the position of Figure 5^b and completing the cycle. Obviously the locking lug 81 comes into action again to lock the frame 62 from moving forwardly so that toggle levers 67, 67 which are locked in straightened position (Figure 8) will be flexed by the forward endwise movement of the connecting link 68, thus releasing the breaker jaw 65, so that the stack A' may be ejected.

15 There is one feature that is of sufficient importance to be further emphasized, namely, the arrangement of the sheets in the gum pile A and the relation of the sticks at the instant of breaking. While the sticks have 20 been generally described as arranged in vertical rows or stacks, this arrangement is only approximate, since the sticks constituting each vertical stack are actually inclined to the vertical, and away from the advancing 25 end of the pile. In other words, the successive sheets of the pile from top to bottom are slightly offset endwise so that the score lines, or lines of breakage are inclined to the vertical, as is clearly shown in Figures 7 and 8. This arrangement of the sheets is 30 therefore purposely provided for, in order to facilitate the breaking action by bringing about a condition wherein a slight bending movement is only necessary to make a 35 clean break along the score lines.

Manifestly in a machine of this character the entire mechanism and particularly the cams are accurately designed and set so that the parts actuated thereby, are moved at the 40 proper instant in the cycle of operation, travel at a predetermined speed and through a predetermined distance. Thus having clearly in mind the various steps constituting each cycle and their order of functioning 45 it is a matter of timing the cam action, to obtain a smooth and perfect automatic operation. In treating of the operation of the machine, the action of each mechanism and its relation to the mechanisms closely associated therewith, have been described independently, but ample reference has been 50 made to the contemporary action of the other mechanisms so that a clear conception of the action of the entire machine can be 55 readily grasped.

As is invariably the case in designing automatic machinery, a choice of mechanical movements and combinations, arrangement of parts is always available and for this 60 reason the machine herein described will permit of considerable modification without departing from the spirit of the invention. Therefore it is not intended that the invention is to be limited to the disclosure herein

except in so far as it is specifically set forth 65 in the appended claims.

We claim:

1. In a machine of the character described, the combination of a material supporting table, means for maintaining a pile of the 70 material in sheet form on said table, means for intermittently advancing said pile endwise a predetermined distance, and breaking mechanism acting intermittently to grip and break the advanced end portions of said pile. 75

2. In a machine of the character described, the combination of a supporting member adapted to support a pile of sheets of the material to be broken, said pile uniformly decreasing in depth from end to end, means 80 for feeding sheets of a predetermined number of units onto said pile, and means for breaking portions from the deeper end of said pile, said feeding and breaking means acting intermittently and in alternate sequence.

3. In a machine of the character described, the combination of a supporting member adapted to support a pile of sheets of the material to be broken, sheet feeding means 90 and breaking means located adjacent said supporting member, and means for advancing said pile to said breaking means after each sheet feeding operation, whereby an end portion of said pile equal in quantity to 95 the amount fed to the pile, is successively removed.

4. In a machine of the character described, the combination of a supporting member adapted to support a pile of sheets of the 100 material to be broken, means for imparting bodily endwise movement to said pile, means for successively feeding sheets onto said pile in one position thereof, and means operating in another portion thereof to break 105 stacks of superimposed pieces from the end of the pile equal in quantity to the material in each sheet added to the pile.

5. In a machine of the character described, the combination of a supporting member 110 adapted to support a pile of sheets scored transversely into units, said pile uniformly decreasing in depth from end to end by the shortening of each sheet by one unit, means for feeding sheets of a predetermined number of units onto said pile, and means for breaking successive stacks of superimposed 115 units from one end of the pile, said units being equal in number to the units in each sheet fed to said pile.

6. In a machine of the character described, the combination of a supporting table adapted to support a pile consisting of a predetermined number of sheets of the material to be broken, means for advancing 125 said pile endwise on said table, breaking mechanism located adjacent the forward end of said table, said sheet feeding means,

pile advancing means and breaking mechanism co-acting to successively feed, advance and break a predetermined amount of the material from the end of said pile.

7. In a machine of the character described, the combination of a supporting table adapted to support a pile of sheets of the material to be broken, means for intermittently advancing said pile endwise a predetermined distance, a breaking member acting intermittently to grip and break the advanced portion of said pile, and means for discharging said broken portion from said breaker member.

8. In a machine of the character described, the combination of a material supporting member on which the material in the form of scored sheets is piled, so that each successive sheet from top to bottom of said pile is shortened at one end by a predetermined amount, an oscillating breaker member located adjacent the opposite end of said pile, and means for advancing said pile into the path of said breaker member whereby vertical rows of the material is successively broken along the score lines from the advanced end of said pile.

9. In a machine of the character described, the combination of an inclined sheet supporting table and adapted to support a pile of sheets of material scored transversely to form a predetermined number of smaller units, means for feeding sheets onto said pile, means for intermittently advancing the pile endwise, a distance equal to the width of one unit, and breaker mechanism operating to remove the end vertical row of units after each advance movement of said pile.

10. In a machine of the character described, the combination of a member for supporting a pile of the material to be broken, in the form of sheets, sheet feeding mechanism, pile advancing mechanism and breaking mechanism, said mechanisms being operative in cycles, to successively break from the end of the pile a quantity of the material equal to that fed to the pile during each cycle.

11. In a machine of the character described, the combination of a supporting table, means for feeding scored sheets of the material onto a pile supported on said table, means for intermittently advancing the pile horizontally through a distance equal to the distance between score lines, breaker mechanism acting to bend and break the material at successive score lines, and means for ejecting the broken material from the breaker mechanism.

12. In a machine of the character described, the combination of a pile supporting member, means for intermittently feeding sheets of the material to be broken, on the top of said pile, means for intermittent-

ly advancing said pile a predetermined distance forwardly after each sheet is added, and mechanism acting to intermittently break and remove the advanced end portions of said pile.

13. In a machine of the character described, the combination of a pile supporting member, means for intermittently feeding sheets of the material to be broken, onto said pile, said sheets consisting of smaller units connected by parallel score lines and mechanism acting to break and remove a vertical row of units from one end of said pile, after each feeding operation, said row consisting of the same number of units constituting each sheet as fed to said pile.

14. In a machine of the character described, the combination of a supporting member adapted to support a pile of scored sheets of gum, consisting of connected sticks, one end of said pile being the full thickness of the sheets, each sheet being reduced by one stick toward the other end of the pile, means acting intermittently to feed sheets onto said pile, and means for breaking rows from the thick end of said pile after the addition of each sheet.

15. In a machine of the character described, the combination of a table adapted to support a pile of sheets of gum, scored transversely to form connected sticks, means for feeding sheets or a predetermined number of sticks onto said pile, means for intermittently advancing said pile endwise a distance equal to the width of one stick, whereby each sheet from top to bottom of the pile is reduced in length by one stick, and breaker mechanism acting intermittently to break rows of sticks from the advancing end of said pile, the number of sticks in each row being equal to the number of sticks in each sheet as they are fed to said pile.

16. In a machine of the character described, the combination of an inclined table and adapted to support a pile of scored sheets of gum, each consisting initially of a predetermined number of connected sticks, and said pile arranged so that each sheet from top to bottom is reduced in length from one end of the pile by one stick, means for intermittently feeding sheets onto said pile, means for advancing said pile forwardly a distance substantially equal to the width of one stick, and means for breaking and removing a vertical row of sticks from the forward end of said pile, after each advancement.

17. In a machine of the character described, the combination of a magazine adapted to contain a supply of sheets, scored transversely to form a predetermined number of connected sticks, a table adjacent said magazine adapted to support a pile of said sheets, means for feeding the sheets from

said magazine onto said pile, means for advancing said pile endwise after each feeding operation, and breaker mechanism located adjacent one end of said table and 5 operating intermittently to break and remove the vertical row of sticks from the advanced end of said pile.

18. In a machine of the character described, the combination of a supporting 10 table, sheet feeding mechanism associated with said table, and adapted to feed scored sheets of the material consisting initially of a predetermined number of connected sticks, said sheets being deposited on top of a pile 15 in which the sheets are graduated from end to end, and from top to bottom by one stick, and co-acting mechanisms for successively adding a sheet to the top of the pile, advancing the pile forwardly, and breaking 20 the advanced vertical row of sticks from said pile.

19. In a machine of the character described the combination of a table adapted to support a pile of scored sheets of gum, 25 feeding mechanism for supplying sheets to the top of said pile, means for advancing the pile a predetermined distance along said table, and breaker mechanism acting to successively bend and break the advanced end 30 portion of said pile, along the vertically aligned score lines.

20. In a machine of the character described, the combination of a vertical delivery chute, a magazine adapted to retain 35 a supply of scored sheets of gum, means for discharging the sheets from said magazine, means for supporting the sheets in a vertical pile, and a breaker mechanism adjacent one end of said pile and comprising an oscillating breaker member having fixed and 40 movable jaws, adapted to bend and break successive piles of sticks from the end of said pile, during the oscillation thereof toward said pile, and co-acting mechanism for 45 releasing said jaws and ejecting the sticks from said member during the return oscillation.

21. In a machine of the character described, the combination of a supporting 50 table, means for maintaining a pile of sheets of the material on said table, a transporting member operative to intermittently engage the bottom of the pile and advance the same in a horizontal direction and through a pre- 55 determined distance along said table, an oscillating breaker member mounted at the end of said table and operating to break successive end portions from said pile and means for ejecting the broken material from 60 said breaker member.

22. In a machine of the character described, the combination of a table adapted to support a pile of sheets of the material to be broken, means for feeding sheets onto 65 said table, a rotative transporting member

adapted to engage said pile and advance it bodily along said table, and through a predetermined distance, a breaker member mounted for oscillatory movement adjacent the table, and comprising jaws between which the end of the pile is advanced at the end of each forward oscillation, means for actuating the jaws to grip and break the end portion of the pile, and means for releasing the jaws and ejecting the material gripped thereby. 70

23. In a machine of the character described, the combination of a pile supporting member, means for feeding sheets of material onto said pile, means for advancing said pile endwise, and through a predetermined distance, and breaker mechanism mounted at the end of said pile supporting member and comprising fixed and movable jaws, and means for actuating the movable 80 jaw members into clamping engagement with the end portion of the pile after the fixed jaw has engaged and bent the same at an angle to the pile. 85

24. In a machine of the character described, the combination of an inclined pile supporting table adapted to support a pile of scored sheets of gum each consisting initially of a predetermined number of connected sticks, means for intermittently feeding sheets onto said pile, means for advancing the pile bodily after each feeding operation a predetermined distance beyond one end of the table, an oscillating breaker member mounted at the end of said table, and 100 having a recess adapted to engage and bend the advanced end portion of said pile along the endmost score lines, means operative after the bending operation to clamp the bent end portion in the breaker member, 105 whereby the same is broken from the end of the pile, and means for releasing and ejecting the broken end portions from the breaker member. 110

25. In a machine of the character described, the combination of a table for supporting a pile of sheet material adapted to be broken along parallel score lines, means for feeding the sheets onto said pile, a breaker member mounted adjacent one end of said table, mechanism for oscillating said breaker member, mechanism for advancing said pile toward said breaker member, the latter acting in its forward movement to bend the end portion of the pile along the end-most score lines, and a clamping jaw carried by said breaker member, and operative to clamp the bent end portion of the material whereby the same is broken from the pile in the return movement of said breaker member. 115 120 125

26. In a machine of the character described, the combination of a magazine in which a supply of scored sheets is maintained, means for feeding the sheets from a slot at the base of said magazine and com- 130

- prising relatively movable pusher and carrier plates, cam actuated mechanism connected with said plates, a table adjacent said magazine, and adapted to support a pile onto which the sheets are successively discharged, and mechanism operating intermittently and during the interval between each sheet feeding operation to break the end-most scored portions from one end of the pile.
27. In a machine of the character described, the combination of stationary table, a pile of scored sheets supported on said table, mechanism associated with said table for advancing said pile bodily on said table, oscillating breaker mechanism mounted adjacent the table and operative after each advance movement of the pile to break the advanced end portion from said pile, and ejecting mechanism associated with said breaker mechanism, and actuated by said sheet feeding mechanism for ejecting the broken end portion from said breaker mechanism, simultaneously with the feeding of a sheet onto said pile.
28. In a machine of the character described, the combination of a sheet supply magazine, a table, a pile of scored sheets supported on said table, a discharge chute, a main drive shaft, a plurality of cam actuated mechanisms driven from said shaft, and comprising sheet feeding mechanism associated with said magazine, pile transporting members associated with said table, oscillating breaker mechanism located at one end of said table, and ejector mechanism associated with said breaker mechanism, said mechanisms being actuated successively in the order named and in cycles, whereby during each cycle, a sheet is fed to the pile, the pile advanced bodily toward said breaker mechanism, a vertical stack of material broken along vertically aligned score lines from the end of the pile, and the same ejected into said chute.
29. In a machine of the character described, the combination of stationary pile supporting member, means for alternately feeding scored sheets onto said pile and advancing the pile bodily along said table, whereby a constant quantity of material is maintained in said pile, breaker mechanism acting after each pile advancing operation to break the end vertical row of scored elements from the pile, and ejector mechanism acting after each breaking operation and simultaneously with the succeeding sheet feeding operation, to eject the contents from said breaker mechanism.
30. In a machine of the character described, the combination of a material supporting table, a magazine adjacent said table in which sheets of the material are piled, means for intermittently ejecting the bottom sheet from said magazine onto the top of a pile supported on said table, and means for breaking the end portion from said pile, after each sheet is added.
31. In a machine of the character described, the combination of a material supporting table, a magazine adjacent said table in which sheets of the material are piled, means for intermittently ejecting the bottom sheet from said magazine onto the top of a pile supported on said table, means for intermittently advancing said table forwardly after each sheet is added, and means acting intermittently to break the advanced end portion from said pile.
32. In a machine of the character described, the combination of a material supporting table, a magazine adjacent said table in which sheets of the material are piled, means for intermittently ejecting the bottom sheet from said magazine onto the top of a pile supported on said table, and comprising a carrier plate movable in a horizontal plate towards and from said pile, and constituting the bottom wall of said magazine, and a pusher plate superimposed upon said carrier plate and adapted to engage the rear edge of the bottom sheet in said magazine, and means for reciprocating said plates.
33. In a machine of the character described, the combination of a material supporting member adapted to support a pile of material, means for feeding successive sheets of material onto said pile, means for intermittently advancing said pile, means for breaking the end portion of said pile after each advance movement of said pile, and means for clamping said pile to said supporting member during the breaking operation.
34. In a machine of the character described, the combination of a material supporting member adapted to support a pile of material, means for feeding successive sheets of material onto said pile, means acting intermittently to break one end portion from said pile, and a clamping member operative to clamp said pile against said supporting member during the action of the breaking means.
35. In a machine of the character described, the combination of a material supporting member adapted to support a pile of material to be broken, means for feeding successive sheets of material onto said pile, a breaker member mounted adjacent said supporting member, means for intermittently advancing said pile toward said breaker member, and a clamping plate mounted above said pile and operative during the action of said breaker member, to clamp said pile against movement relative to the pile supporting member.
36. A machine for the purpose described, comprising means for supporting a quantity of gum in the form of a pile of sheets scored transversely to form a predetermined num-

ber of connected sticks, each sheet below the top sheet having one stick removed from one end, thereby reducing the bottom sheet to a single stick, means for successively feeding sheets onto said pile and means for successively breaking the sticks from the one end of each sheet together with the bottom sheet, the sticks thus removed being equivalent to the number of sticks in the sheets as fed onto said pile.

37. A machine for the purpose described, comprising co-acting mechanisms operating alternately to augment a pile of scored sheets of gum supported in said machine by the addition of sheets to said pile, and to deplete said pile by the breaking of the end portions from the sheets of said pile, the number of sticks broken therefrom being equal to the number added thereto in sheet form.

38. In a machine of the character described, the combination of means for supporting the material to be broken in the form of plurality of scored sheets superimposed upon each other with the corresponding score lines offset to register with lines of breakage inclined to the vertical and breaker mechanism acting to bend and break successive end portions along said inclined lines of breakage.

39. In a machine of the character described, the combination of means for supporting a plurality of sheets of gum scored to form a plurality of connected sticks, said sheets being superimposed with corresponding lines of scoring, inclined to the vertical, and a breaker member for bending and breaking successive end portions from the end of said pile and along said inclined score lines.

40. A machine of the character described,

comprising means for arranging a plurality of scored sheets of gum into a pile with corresponding score lines offset to provide lines of breakage inclined to the vertical, and means for reducing said pile into sticks, by bending and breaking the endmost stacks of sticks along said inclined lines of breakage.

41. A machine for the purpose described, comprising means for intermittently feeding sheets of gum onto a pile, means for positioning the top sheet to maintain a predetermined relation of the sheets in said pile and means for breaking superimposed end portions from said pile.

42. A machine for the purpose described, comprising a pile supporting member, means for feeding sheets of gum onto said pile, said sheets being scored to form connected sticks, means for positioning each sheet as it is fed to said pile, to establish vertically inclined lines of breaking coinciding with the corresponding score lines of the several sheets, means for intermittently advancing said pile endwise, and breaker mechanism acting intermittently to bend and break successive end portions from said pile and along said inclined lines of breakage.

43. A machine of the character described, comprising means for maintaining a constant supply of scored sheets of gum in pile form, and means for continually reducing said pile to sticks arranged in superimposed relation, and means for ejecting said sticks from said machine.

In witness whereof, we hereunto subscribe our names this 19th day of September A. D., 1923.

WILLET B. RANNEY.
ARTHUR E. JOHNSON.
